UNITED STATES PATENT OFFICE.

ARTHUR H. SKAER, THEODORE E. BARKER, AUGUST H. KATTERJOHN, AND OMAR E. CLARK, OF DENVER, COLORADO, ASSIGNEES, BY MESNE ASSIGNMENTS, TO GARDNER-DENVER COMPANY, OF QUINCY, ILLINOIS, A CORPORATION OF DELAWARE.

ROCK DRILL.

Application filed July 11, 1922. Serial No. 574,193.

The present invention relates more particularly to rock drills of the type having a motor for operating on the drill steel and another motor for effecting the rotation of the steel. In certain types of construction where the steel sticks in the hole and the steel rotating motor continues in operation a relatively great amount of strain is produced upon the transmission gear between the motor 5 and the chuck which is apt to result in stripping the gears.

One of the primary objects of the present invention is to provide a structure by which this difficulty is entirely overcome.

One embodiment of the invention is illustrated in the accompanying drawings, wherein:—

Figure 1 is a view in elevation of the front portion of a well known type of hammer drill 20 with the head plate of the chuck rotating motor removed,

Figure 2 is a cross sectional view therethrough,

Figure 3 is a plan view with the motor 25 shown in section,

Figure 4 is a longitudinal sectional view,

Figure 5 is an edge view of the spring washer employed,

Figure 6 is a face view of the same,

Figures 7, 8 and 9 are detail sectional views, 30 respectively, illustrating different types of slip connections.

In the embodiment disclosed in Figures 1 to 6, the drill includes a suitable cylinder 35 member 10 containing a hammer piston 11 having an extension 12. A hood 13, carried by the front end of the cylinder member 10, houses a rotatable tool holder in the form of a chuck sleeve 14. This sleeve is provided with 40 a socket 15 adapted to receive the rear end of a drill steel 16 that is loosely fitted in the chuck sleeve and is suitably interlocked therewith so as to rotate with said sleeve in a manner well understood. The hammer extension 45 12 of the piston 11 in the present embodiment is adapted to strike the rear end of the drill steel 16, as illustrated in Figure 4.

A drill rotating motor is located on the 50 cylinder member 10, and as shown, consists of a housing 17 containing intermeshing gear pistons 18. Motive fluid is supplied to the housing 17 on one side of the piston through a passageway 19, and a suitable exhaust 20

allows the escape from the opposite sides. 55 Connected to one of the gear pistons 18 is a shaft 21 provided with a worm 22 that is in mesh with a worm wheel 23 rotatably mounted on the rear end of the chuck sleeve 14. Said chuck sleeve is reduced in diameter to receive said worm wheel, thereby providing an abutment shoulder 24 for one side of said worm wheel 23. A friction washer 25 may be interposed between the abutment shoulder and the worm wheel. The rear 60 65 terminal portion of the sleeve 14 is threaded to receive a nut 26 forming an abutment on the opposite side of the worm wheel 23 of the abutment shoulder 24, and interposed between said nut 26 and the wheel are friction 70 washers 27 and a spring washer 28, the latter being preferably formed in oppositely disposed curves, as shown in Figures 5 and 6.

The friction washers 25 and 27 and the spring washer 28 provide a friction clutch 75 or slip connection between the worm wheel 23 and the chuck sleeve 14. This connection is relatively tight or fast, so that under ordinary conditions the rotation of the gear pistons 18 will transmit motion to the shaft 21, 80 and thence through the worm 22 to the worm wheel 23, and this worm wheel will be, in effect, fixed to the chuck 14, so as to insure its rotation and consequently the rotation of the drill steel. In fact, when the drilling piston 85 11—12 is inactive, the clutch or slip connection is such that the motor will stall if the drill steel becomes stuck before the slip connection will give materially.

In operation, however, as long as the hammer piston 11—12 is in operation rapidly repeated blows delivered against the drill steel 90 will cause a vibration of the machine which appears to lessen the tractive or friction connection between the worm wheel 23 and chuck 95 sleeve 14, so that while the drill steel will be rotated under normal conditions, if it becomes stuck and the hammer piston continues to operate, the drill rotating motor will continue to move and the slip connection will permit the worm wheel to rotate with respect to the chuck sleeve 14. This has proven a very material advantage, for if the worm wheel 23 is fast to the chuck sleeve 14, it has been found that the operation of the drill rotating pistons 18, coupled with the vibration of the drill due to the piston 11—12, causes a continued rotation of the worm, even though the 100 105

worm wheel is stopped. As a consequence the thread of the worm acts as a wedge and in time bears with such great pressure against the teeth of the worm wheel that either the worm or the worm teeth are apt to be stripped. Experience has demonstrated that this is entirely overcome by the present construction. While, therefore, it is peculiarly effective in connection with the worm gearing, it is also of utility with other types.

As suggested modifications of the above described structure, attention is invited to Figures 7, 8 and 9. In Figure 7 the chuck sleeve element is designated 14^a, and rotatably mounted thereon is the worm wheel 23^a operated by the worm designated 22^a. A friction washer 25^a is interposed between one side of the worm gear 23^a and the abutment shoulder 24^a, while another friction washer 27^a has a bearing against a washer 28^a held by a nut 26^a. In Figure 8 the chuck element 14^b has a shoulder 24^b and rotatably mounted on said element 14^b is the worm wheel 23^b engaged by the worm 22^b. The inner side of the worm wheel is tapered, and bearing against the beveled faces are friction washers 25^b and 27^b, the former bearing against the abutment shoulder 24^b, and the latter being held in place by a nut 26^b. In Figure 9 the chuck element 14^c has a shoulder 24^c, and is rotatably surrounded by a worm wheel 23^c, the inner face of which is beveled. A friction washer 25^c is interposed between one side of the worm wheel 23^c and the shoulder 24^c. Bearing against the inner beveled face of the worm wheel 23^c is another friction washer 27^c within which is located a cone or wedge element 28^c that is borne against by a holding nut 26^c. The worm which engages the worm wheel 23^c is shown at 22^c. Obviously these three modifications perform the same functions as the embodiment first described.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or scope of the invention.

Having thus fully described our invention, what we claim as new and desire to secure by Letters Patent, is:—

1. In rock drilling apparatus, the combination with a rotatable drill chuck, of a drilling motor for operating on a steel in the chuck, and means for rotating the chuck, including a worm gear surrounding a portion of the chuck, a driving worm engaged with the worm gear, and a slip connection between the worm gear and chuck.

2. In rock drilling apparatus, the combination with a rotatable drill chuck, of a drilling motor for operating on a steel in the chuck, and means for rotating the chuck, including a motor independent of the drilling motor, a worm rotated by the motor, a worm gear driven by the worm and mounted to rotate on the chuck when the chuck is held against rotation, an abutment on the chuck for one side of the worm gear, another abutment on the other side of the worm gear, and a slip connection between the latter abutment and the worm gear.

3. In a rock drilling apparatus, the combination with a rotatable drill chuck sleeve having an abutment, of a drilling motor for operating on a drill steel placed in the sleeve, and means for rotating the sleeve, including a gear wheel mounted to rotate on the sleeve and having an abutment bearing against the sleeve, and a friction device interposed between the gear wheel and the first mentioned abutment to normally transmit rotary motion from the gear wheel to the sleeve, but permit the former to continue rotation when the sleeve is held against rotation by reason of the stoppage of the drill steel.

4. In rock drilling apparatus, the combination with a rotatable chuck having means therein for loosely interlocking with a drill steel placed therein, of a drilling motor including a hammer piston that delivers rapidly repeated hammer blows upon a steel placed in the chuck, a gear mounted to rotate on the exterior of the chuck when the chuck is held against rotation, a chuck rotating motor geared to said gear, and a friction slip coupling between the gear and the chuck upon which it is mounted for normally causing the chuck to be rotated by the gear.

In testimony whereof, we affix our signatures.
